UNITED STATES PATENT OFFICE.

JAMES J. MCGUIRE, OF ST. LOUIS, MISSOURI

THERMOSTATIC VALVE.

1,123,208.

Specification of Letters Patent. Patented Dec. 29, 1914.

Application filed April 20, 1914. Serial No. 833,213.

To all whom it may concern:

Be it known that I, JAMES J. MCGUIRE, a citizen of the United States, residing at St. Louis, Missouri, have invented a certain new and useful Improvement in Thermos- 5 static Valves, of which the following is a full, clear, and exact description, such as will enable others skilled in the art to which it appertains to make and use the same.

10 This invention relates to thermostatic valves, and more particularly to that type which are commonly known as steam traps, and which are arranged on the radiators in steam-heating systems for permitting the 15 escape of air and water of condensation from the radiators when the steam is turned into same, but which automatically close when the steam comes in contact therewith. It has heretofore been the general practice 20 to make the valve-actuating means in a thermostatic valve of the type referred to, in the form of a flexible walled chamber of circular shape and to fill, or partially fill, it with a liquid having a low boiling point, such as, 25 for example, alcohol, the vapor pressure of which expands the walls of the chamber when the same is subjected to heat, and thus actuates the valve that is carried by said chamber. The usual manner of constructing, 30 the chamber is to arrange a pair of curved or cupped disks, one above the other, so as to provide the hollow chamber between the walls thereof, and then to fasten the meeting edges of said disks together by 35 means of crimping, folding, riveting or soldering. By the use of the methods mentioned in forming the chamber, the point at which the disks are secured together is composed of two or more thicknesses of metal, 40 or is made heavy and rigid by the use of rivets or solder, consequently, this point resists the action of the expansive medium contained in the chamber; in other words, if the chamber is composed of a pair of 45 disks which are connected together at their meeting edges by means of crimping, a seam or ring is formed about the outer edge of said chamber that is composed of several thicknesses of metal. Any pressure created 50 in the expansion chamber of course tends to force the top and bottom walls thereof apart, and in order to do this, the metal must either stretch, or the outside diameter of said chamber must decrease. By securing 55 the meeting edges of the disks together in

the manner above described a substantially rigid ring is formed around the chamber which resists the action of the expansive fluid, and thus retards greatly the action of the valve.

60 In valves of the construction just above described very high pressure has to be created inside of the expansion chamber before the valve will operate, owing to the resistance offered by the diaphragm. This, of course, is a very objectionable feature, as in the case of steam traps a considerable quantity of steam is allowed to escape before enough pressure is created in the expansion chamber to close the valve. Another objectionable feature of the valves now in general use is the fact that the constant strain on the joint between the disks either opens up the joint or breaks the disks after being in use a short time. Attempts have been made 65 to overcome these defects in thermostatic valve construction by forming the disks with circular corrugations or fluted portions, but these have not entirely overcome these defects, and furthermore, have added 70 another defect which is that of having the disks expand unequally, or to expand on one side of the center first, which results in a cocked valve which will not seat properly.

75 In order to overcome the objections above outlined, I have devised my present invention, the main object of which is to provide a valve of the type referred to that is more flexible and more sensitive to changes in temperature, and consequently more rapid 80 in its action of automatically opening and closing, than the valves now in general use.

85 Another object is to provide a valve of the character described in which the flexible disk or diaphragm which carries the valve proper is so constructed that the liability of 90 breakage due to constant flexing and bending is reduced to a minimum.

95 Still another object is to provide a valve of the character described that is provided 100 with novel means for adjusting the position of the valve proper with relation to its co-operating seat, whereby said valve can be readily changed to suit different requirements.

105 Other objects and desirable features of my invention will be hereinafter pointed out.

110 Figure 1 of the drawings is a vertical sectional view of a thermostatic valve con-

structed in accordance with my invention. Fig. 2 is a similar view illustrating a different method of supporting the expansion chamber in the valve casing. Fig. 3 is a view similar to Fig. 1 illustrating a slightly different method of constructing the expansion chamber; and, Fig. 4 is a vertical sectional view showing my improved expansion chamber arranged in an inverted position in the valve casing, said chamber being of slightly different construction from that shown in Fig. 1.

Referring to Fig. 1 of the drawings, which illustrates one form of my invention, A designates the valve casing which may be of any suitable construction, and which is provided in its side wall with a perforated boss 1 that is adapted to be connected to a steam radiator, or similar apparatus (not shown), so as to admit steam to the interior of said casing. The valve-carrying member or expansion chamber B is supported inside of said valve casing, said chamber comprising a cup-shaped portion 2 provided with a flexible closure or diaphragm 3 at its lower end, said flexible closure carrying the valve proper 4, which is adapted to coöperate with a valve seat 5 formed in the outlet 6 in the bottom wall of the casing A. The valve 4 is preferably adjustably connected to the diaphragm 3, and in the embodiment of my invention herein shown said diaphragm is provided with a stem 7, which has a threaded portion 8 that coöperates with a correspondingly threaded recess formed in the valve 4. The cup-shaped portion 2 of the expansion chamber B is provided at its lower end with an outwardly projecting annular flange 9, said flange being preferably reduced in thickness toward its outer edge, and the diaphragm 3 is bent inwardly from its point of greatest diameter so as to form an annular, horizontally disposed, U-shaped portion 10 that fits loosely over the flange 9, the inner edge of the inwardly bent portion being either brazed or soldered to the cup-shaped portion 2, as indicated at 11. The expansion chamber B is preferably partially filled with a suitable expansive fluid α , and when said chamber is exposed to the heat from the steam which enters the valve casing through the opening 1, the liquid α will expand or vaporize, and thus create pressure inside of the chamber B, which tends to force the diaphragm 3 downwardly to seat the valve 4, thus preventing the escape of steam through the outlet 6. The curved portion 10 of the diaphragm 3, lying outside of the point of connection between said diaphragm and the expansion chamber, and being normally spaced away from the flange 9, renders said diaphragm extremely sensitive to changes in temperature in the casing A, and a very slight pressure created in said chamber is sufficient to force the dia-

phragm 3 outwardly to close the valve 4, as there is no thickened portion of metal or other hindrance at the marginal edge of the diaphragm to prevent the curved portions 10 from readily yielding when subjected to 70 pressure.

The expansion chamber B may be supported in the valve casing A in various ways, one convenient method being that shown in Fig. 1, wherein the portion 2 is 75 provided with a threaded bolt or rod 12 that is screwed into the upper wall thereof and which projects upwardly therefrom and has a threaded engagement with a removable cap α of the valve casing A. The bolt or rod 12 80 preferably extends downwardly in the chamber B to within a short distance from the diaphragm 3 so as to prevent said diaphragm from being forced upwardly into the chamber B by any excessive pressure in 85 the casing A. By the construction just described the expansion chamber B can be quickly removed from or inserted into the casing A, by simply unscrewing the cap α , and said chamber can be readily adjusted 90 with respect to the cap α so that the desired relation between the valve 4 and its corresponding seat 5 can be obtained.

Under certain conditions in service it is desirable to have a portion of the valve-carrying member or expansion chamber exposed to the atmosphere so that said chamber will cool off more quickly when the steam ceases to flow into the valve casing. In Fig. 2 I have illustrated such a construction wherein the expansion-chamber B' is provided with an externally threaded portion δ that coöperates with an internally threaded cap α' , which is threaded into the valve casing A'. 100

Where valves of large diameter are necessary it has been found that the simple method of soldering or brazing the diaphragm 4 onto the cupped shaped portion 2 of the expansion chamber is sometimes 110 insufficient to maintain a tight joint at the point of connection, and in order to reinforce and strengthen the joint between the diaphragm and the portion 2, I provide a clamping nut 13 that is screwed down over 115 a threaded portion 14 formed on the side wall of the portion 2, and thus, securely clamps the edge of the diaphragm 3 against the flange 9, as shown clearly in Fig. 3. If desired a coiled expansion spring 15 may 120 be interposed between the diaphragm 3 and the bottom wall of the casing A, so as to assist in returning the valve 4 to its open position.

In Fig. 4 I have illustrated a construction wherein the valve 4 is designed to operate in an inverted position in the casing A², and the expansion chamber B² is provided at its open end with a plurality of arms or ribs 16 which prevent the dia- 130

phragm from being forced into the chamber B² because of any excessive pressure in the valve casing A².

While I have herein shown the valve 4 as being provided with a conical portion that co-operates with the conical seat 5, I do not wish it to be understood that my invention is limited to such a construction, as said valve and its corresponding seat may be of any desired shape without departing from the spirit of my invention.

From the foregoing it will be seen that I have devised a thermostatic valve that is very simple in construction, more efficient in operation than the valves now in general use, and which is so constructed that there are no seams or thickened portions on the valve-actuating means to retard the action of the valve, or to be subjected to breaking strains in service.

Having thus described my invention, what I claim is:

1. A valve-actuating means for thermostatic valves, consisting of an expansion chamber that is comprises rigid top and side walls, said side wall being provided at its lower end with an annular flange, and a bottom wall that is connected to said side wall at a point above said flange, said bottom wall being provided with a valve and a substantially U-shaped marginal portion that surrounds said flange and lies wholly without said side wall and which is free to bend independently of said flange.

2. In a device of the character described, a casing having a steam inlet and an outlet passage, said outlet being provided with a valve seat, a valve that co-operates with said seat, and a valve-actuating means comprising a cup-shaped member provided at its lower end with a rigid annular flange and a flexible member that lies across the lower portion of said cup-shaped member and which is attached to said valve, said flexible member being provided with a portion that is bent around and normally spaced away from said flange.

3. In a device of the character described,

a cylindrical, cup-shaped expansion chamber provided at its open end with a rigid 50 annular flange, and a cylindrical diaphragm that lies across the open end of said chamber, said diaphragm being provided with a marginal U-shaped portion that surrounds said flange, the internal diameter of said 55 U-shaped portion being greater than the external diameter of said flange.

4. In a device of the character described, an expansion chamber provided with an annular flange, a diaphragm that closes the 60 lower portion of said chamber, said diaphragm having its marginal edge turned inwardly and connected to the outer wall of said chamber, and means for clamping said diaphragm against said flange. 65

5. In a device of the character described, an expansion chamber provided with an outwardly projecting annular flange adjacent its lower end and having a screw-threaded portion on the outer wall thereof, 70 a diaphragm extending across the lower wall of said chamber and having its marginal edge bent inwardly over said flange, and a nut that co-operates with said screw-threaded portion to clamp said diaphragm 75 against said flange.

6. In a device of the character described, an expansion chamber consisting of a cylindrical member whose top and side walls are rigid, an outwardly extending rigid annular flange arranged at the base of said side wall, and a diaphragm whose central portion lies across the bottom of said cylindrical member below said flange, the marginal edge of said diaphragm being curved 80 upwardly and inwardly and connected to said side wall at a point above said flange, the curved portion of said diaphragm being spaced away from said flange. 85

In testimony whereof I hereunto affix my 90 signature in the presence of two witnesses, this seventeenth day of April 1914.

JAMES J. McGuIRE.
